WATERPROOF WATCHCASE

Hyman Dinstman, New York, N. Y., assignor to
I. D. Watch Case Co., Inc., New York, N. Y.

Application April 14, 1949, Serial No. 87,407

2 Claims. (Cl. 58—90)

1

This invention relates to new and useful improvements in watertight watchcases and, more particularly, the aim is to provide a novel and valuable such case incorporating an improved means for clamping in place, tightly below the bezel, the so-called crystal, the latter a transparent member of glass or other suitable material; the present improvements being characterized by a securing means for the parts and adapted to compress in an ideal manner a contained gasket or packing (of rubber, a suitable plastic or other preferably stiffly elastic compressible material), thereby to obtain a markedly effective watertight casing for the working parts of the watch.

According to the present invention, the use of screws or the like is entirely avoided, as well also as the use of a fairly large plurality of dowels; but, instead, as the present invention may be and preferably is carried out, there are employed as the male members of said securing means merely two thin pins unheaded at both ends, and hence substantially not observable as present at all; with, moreover, the arrangement such that while said pins may be deliberately instantaneously inserted into their appointed receptors, thereafter to be held immovable in the latter yet merely by way of friction, subsequent casual or accidental removal or displacement of either pin is impossible unless the watchcase parts are later deliberately brought to the same spatial relationship as had to be effected preparatory to said deliberate insertion of said pins.

The invention may be applied to watchcases of various kinds and for various uses, and regardless of their shapings and formations, or their chasing or other embellishment if present; but, as the invention is illustratively disclosed herein, it is shown as applied to wrist watches, with a sufficient number of embodiments of the invention illustrated to indicate various of the many possible different ways of obtaining all the benefits of the invention.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is, on an enlarged scale, a longitudinal section taken through a now favored embodiment, with certain contained parts shown in elevation and with portions of the wrist band indicated in dot and dash lines.

Fig. 2 is a fragmentary top plan of a portion of Fig. 1.

Fig. 3 is a side elevation of Fig. 2.

Fig. 4 is a perspective view showing one of the

2

two like elements constituting the aforesaid thin pins.

Fig. 5 side elevationally illustrates a compression-applying device, in the form of a specially equipped C-clamp, for forcibly establishing the spatial relationship having to be effected preparatory to the aforesaid deliberate insertion of said pins.

Fig. 6 is a detail section taken on the line 10—10 of Fig. 5.

Fig. 7 is a perspective view showing, detached, a special addition to said C-clamp.

Fig. 8 is a view partially in side elevation and partially in longitudinal section, showing another now favored embodiment of the invention.

Fig. 9 is a perspective view of the two channel fitments used in the form of the invention shown in Fig. 8.

Fig. 10 is a view largely in side elevation, but partially broken away, showing the bezel of Fig. 8.

Fig. 11 is a view like Fig. 10, but showing the "band case" or back member of the watchcase as included in the combination of Fig. 8, and with the fitments of Fig. 9 lug-coupled to said back member; this view also including a showing of the conventional access screw and washer, but with these detached from said back member.

Fig. 12 is a detail sectional view showing the waterproof crown bushing, taken on the line 30—30 of Fig. 11.

Fig. 13 is a view similar to Fig. 1, but showing still another now favored embodiment of the invention.

Fig. 14 is a detail section, taken on the line 35—35 of Fig. 13, and showing the crown and a retaining screw for the crown shaft.

Fig. 15, which is a view like Fig. 8, except that the former is entirely a longitudinal section, shows a variation in the cross-sectional shape of the channel fitments and also a variation in the cross-sectional aspect of the crystal encompassing central frame portion of the bezel, relative to the watchcase of Fig. 8.

Fig. 16 is a view similar to Fig. 1, but showing still another now favored embodiment of the invention.

Fig. 17 is a bottom plan view of the last-named embodiment.

The waterproof watchcase, according to the first form of the invention shown in Figs. 1 to 4, includes a back member 20 having at each end an upwardly extended component 21 terminating at its upper extremity in a downwardly facing hook 22, and said member 20 at its bottom is provided with the familiar access screw 23.

The back member 20 has an upper internal continuous perimetral shoulder 24 for positioning the dial 25 of a watch movement 26, the crown of which movement is indicated at 27. Said movement, at its flange 28, is positionally

located by engagement of said flange with an accommodately shaped recess 29 in a frame-like top wall 30 of the member 20.

The crystal, designated 31, is provided with a basal perimetral flange 32.

The bezel, marked as a whole 33, is, like the member 20, preferably cast, and incorporates a main frame-like portion 34. This frame-like portion in the present case, and as best shown in Fig. 1, has two long sides 34' and two shorter sides 34'', one of which is also seen in Fig. 2 at 34''. At each end said bezel integrally carries a pair of laterally spaced horns 35; each pair of such horns being spanned by a cross-pin 36 for connecting, as illustrated, one end portion 31 or 38 of the wrist band.

Each two horns at a side of the bezel 33 are thus end prolongations of the side walls 34' of the frame-like portion of the bezel 33, which side walls are of the same cross-section as shown in Fig. 1 for the end walls 34'' of said frame-like portion 34 of the bezel. The components 21 are of a length to fit nicely between the inner sides of the pairs of horns 35 at the opposite ends of the structure, and, as will be noted from Fig. 1, the shaping of these components 21 and the adjacent end portions of the member 20 are such that the said end walls 34'' nicely fit in place between said components and said member 20.

The hereinbefore mentioned gasket or packing is indicated at 39, and this is nested, as shown in Fig. 1, between the top surfaces of the member 20 and a perimetral marginal portion of the dial 25, on the one hand, and, on the other, the underside of the basal flange 32 of the crystal 31; while an upper perimetral extending and inturned flange on the top of the frame-like portion 34 of the bezel 33 is shaped to bear down on the upper side of said basal flange and also fit closely against the outer vertical wall extending perimetral around the crystal, as shown in Fig. 1.

The bights of the top hooks 22 of the components 21 of the member 20 are semi-circularly rounded to fit the cylindricity of a pair of locking pins 40; a pair of such pins being provided, and these being the hereinabove mentioned thin unheaded securing pins.

For taking the opposite ends of said pins, the horns 35 are alignedly apertured as indicated in Fig. 2, and, as shown at 41 in the case of one of said horns and one of said pins, in Fig. 3.

In the case of each pin 40 and its receiving apertures 41, there is a vertical offsetting as between such a pin and its said receiving apertures, sufficient to permit a pin to be sent readily through its said apertures when opposing forces are applied in the direction of the arrows 43 and 44 in Fig. 1, to a value such that compression of the gasket or packing 39 will be so great that a watertight joint is established at opposite sides of said gasket. Consequently, when said forces 43 and 44 are relieved, the elastic action of the stiffly elastically compressible gasket will, without deteriorating the watertight joint, cause each pin 40 to be irremovably clamped against casual or accidental removal or displacement.

Referring in the latter connection to Figs. 5-7, a very simple and practicable appliance is here illustrated for readily applying said forces 43 and 44, or, more accurately, for applying the force 43 and maintaining the force 44 actually as a reaction factor.

This appliance may be, as shown, a C-clamp 75

45 having the usual fixed jaw 46 and a movable jaw 47 coupled by a ball and socket joint 48 to a screw 49 having a turn-bar 50; said movable jaw 47 being here arranged to be restrained against rotational movement during its advance toward the fixed jaw 46 by means including as shown a fork 51 formed at one end of said jaw 47.

Also, in the case of the appliance 45, the same 10 is shown as having at the top of the jaw 46 a surface which, perpendicular to the axis of the screw 49, is not only fayed or flush or plane, but is topped by a framing addition 52 of fairly soft yet highly resilient rubber and secured in place as by way of a suitable plurality of rivets 53 having upper heads as shown in Fig. 5 and with these heads located well down in the apertures 54 through the addition 52 and the fixed jaw 46 at the appointed locations of said rivets.

The central opening 54^a in said addition 52 is of a size and shape such that with the parts of Fig. 1 inverted, the top arched portion of the crystal 31 may safely lie within said opening and then the upper surface of the addition 52 engages that perimetral portion of the frame-like portion 34 of the bezel 33 which is uppermost in Fig. 1.

Thus, just as the parts have to be subjected to said forces 43 and 44, as by the use of the C-clamp 45, for insertion of the locking pins 40, to establish the assembly as shown in Fig. 1, that assembly has to be subjected to said forces, as again in said clamp, before the pins 40 may be removed.

Referring next particularly to Figs. 8-12, in the embodiment herein shown, the parts to which are applied reference numerals with the suffix *a* added correspond, respectively, to the parts to which have been applied the same reference numerals without such suffix. In this structure, it will be noted, all the advantages of the invention are achieved, yet the components 21 of the bezel are omitted, and, instead, two channel fitments 55 are present, each of these having a rib or lug 56, and with each of the lugs 56 shaped to fit closely in a recess or groove 57 formed across, the exterior of an end wall of the frame-like portion 34^a of the bezel 33^a. Said frame-like portion 34^a, across its opposite ends, is the same cross-section as indicated at the left in Fig. 8; and said portion 34^a, along its sides, is of rectangular cross-section as indicated by the fragmentary elevational showing at the left in Fig. 8. As will further be noted, the crystal 31^a is not centrally domed, as in the case of the crystal 31, but, instead, has a flat central roof portion attended by a perimetral beveling as indicated. Note, also, that here the horns 35^a are of different design than the horns 35.

Referring next particularly to Figs. 13 and 14, in the embodiment here shown, and by which also all the advantages of the invention may be obtained, the parts to which are applied reference numerals with the suffix *b* added correspond, respectively, to the parts to which have been applied the same reference numerals without a suffix in Figs. 1 to 4. In this structure, equivalents of the components 21^b are integral with the back member 20^b, but with these components 21^b so formed, it will be noted, that one of them, the one at the right in Fig. 13, has its hook 22^b in the shape of an inverted triangle, and that the other of them, this at the right in Fig. 13, is constituted as a groove; here again,

it will be observed, a crystal 31^b substantially the same as the crystal 31 is included.

Referring next particularly to Fig. 15, in the embodiment here shown, wherein also all the advantages of the invention may be had, the parts to which are applied reference numerals with the suffix *c* added correspond, respectively, to the parts to which have been applied the same reference numerals without a suffix in Figs. 1 to 4. It will be noted in regard to this structure that, while the frame-like portion 34^c of the bezel 33^c is like the corresponding portion of the bezel 33 and a pair of channel fitments 55^c is present, these fitments have rounded instead of squared-off tops like the channel fitments 55.

Referring next particularly to Figs. 16 and 17, in the embodiment here shown, and likewise by which all of the advantages of the invention are secured, the parts to which are applied reference numerals with the suffix *d* added correspond, respectively, to the parts to which have been applied the same reference numerals without a suffix in Figs. 1 to 4. In this structure, it will be noted, the horns 35^d are of a further different design, and the crystal 31^d is also of a further different design. Moreover, in this structure, the equivalent for the backing member 23 is a backing structure including two separate and preferably separately cast members, so made as to be interfittable to establish the assembly shown; with one of said parts including a perimetrical slightly cupped floor wall portion and with the components 21^d integrally carried by said wall portion, and with the other of the two parts of said backing structure comprising a frame-like sub-structure incorporating a side wall formation continuously extending all around the same and resting at its bottom on the upper rim of such cup and carrying at its top a wall 30^d corresponding to the wall 30.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A waterproof wrist watch case comprising a backing element having an internal perimetral shoulder, a watch crystal having an external perimetral shoulder superimposed on said shoulder of said backing element, a frame-like elastic

5 gasket interposed between said shoulders, a bezel fitted over said crystal and having an internal frame-like portion fitted down on said shoulder of said crystal, a pair of laterally spaced horns 10 extended from opposite ends of said bezel, each pair of horns having laterally aligned holes, components extended upward from the ends of said backing element and between the respective horns of said bezel, pins extended through the holes of said horns and along the outer faces of said components, and downwardly facing hooks continuing from the top ends of said components and fitted over said pins between said horns joining said backing element and said bezel to compress said gasket between said shoulders.

15 2. A waterproof wrist watch case comprising a backing element having an internal perimetral shoulder, a watch crystal having an external perimetral shoulder superimposed on said shoulder of said backing element, a frame-like elastic gasket interposed between said shoulders, a bezel 20 fitted over said crystal and having an internal frame-like portion fitted down on said shoulder of said crystal, a pair of laterally spaced horns 25 extended from opposite ends of said bezel, each pair of horns having laterally aligned holes, components extended upward from the ends of said backing element and between the respective horns of said bezel, pins extended through the holes of said horns and along the outer faces of said components, and downwardly facing hooks continuing from the top ends of said components and fitted over said pins between said horns joining said backing element and said bezel to compress said gasket between said shoulders, said components being of a width to occupy the full space between said pairs of horns and spaced from the ends of said backing element forming pockets between said pairs of horns, and end 30 walls depending from said bezel between said pairs of horns and received snugly within said pockets.

HYMAN DINSTMAN.
